UNITED STATES PATENT OFFICE.

JOSEPH BECKER, OF WASHINGTON, DISTRICT OF COLUMBIA.

COMBINED FOCUS AND FIELD FINDER.

1,178,476.

Specification of Letters Patent.

Patented Apr. 4, 1916.

Application filed June 4, 1901. Serial No. 63,106.

To all whom it may concern:

Be it known that I, JOSEPH BECKER, a citizen of the United States, residing at Washington, District of Columbia, have invented a Combined Focus and Field Finder which permits not only of locating exactly on the plate the object to be photographed, but which also permits of quickly and sharply focusing the same.

10 My present patent application is identified for convenience of reference in my related applications or patents as Case C.

The present specification hereinafter makes specific reference to my earlier related patent applications as follows: Case A, Serial No. 26,647, filed August 11, 1900; Case B, Serial No. 42,957, filed January 12, 1901.

20 My present invention consists mainly in a highly improved "optical focuser" of the type shown in Fig. 30 of my said Case A, such type being characterized by the presence of a cam mounted in a position which is fixed relatively to the stationary image receiving plane of the camera and which is adapted to rotate a mirror that is pivotally mounted on the movable lens carriage.

25 Incidentally, my invention also consists in an improved form of the combined finder lens and prism support seen in Fig. 55 of my said Case A, to constitute in combination with it and other parts a non-projecting focus and field finder.

30 The invention further consists in a special means for offsetting the path of the movable image, either to secure a focus indicating position of exact coincidence, as in Fig. 11 of my said Case B, or to secure a focus indicating position of non-coincidence or alinement, as in Fig. 14 of my said Case B.

35 The general object of my present invention is to provide the common and most compact form of folding camera with an optical focuser that does not in any way complicate or interfere with the ordinary manipulation of the camera, and that does not add to its bulk when the camera is folded up for transportation.

40 In the accompanying drawings: Figure 1 is a side elevation of one form of my folding focusing camera complete. Fig. 2 is a front elevation thereof. Fig. 3 is an enlarged vertical section on line 3—3 of Fig. 2, showing only the focus and field finding attachment. Fig. 4 is an enlarged front elevation thereof. Figs. 5 and 6 are detail

views. Fig. 7 is a face view of a special adjustment of the fixed mirror, by adjustment of the lens upon which it is mounted, the adjustment being angular about a substantially horizontal axis approximately parallel to the camera axis, and perpendicular to the paper in Fig. 7. Fig. 7^a (on Sheet 1) is a fractional front view of a modified form of Fig. 7, in which provision is made for adjusting the inclination of the eye mirror angularly on two perpendicular horizontal axes, and, therefore, on any desired horizontal line as resultant axis of rotation. Fig. 7^b (on Sheet 1) is a vertical section on the vertical meridional plane 7^b of Fig. 7^a. Fig. 8 is a diagram of the optical elements of my improved focusing finder, showing how said elements coöperate to form two substantially equal images *f* and *i* of any given object *d* directionally close by such object, and relatively movable by change in the distance of the object or by change in the relative set of the optical elements. Fig. 9 shows the finder image of a head as it appears to the operator when he uses the apparatus in taking a portrait and in focusing on the person's left eyebrow which is seen fractured in the figure, indicating that the subject is not in focus. Fig. 10 shows the optical elements as they are shown in Fig. 8, but on an enlarged scale to make the detail features of the fixed prism clear. Fig. 11 is a view of my compound form adapted for either long or short focus work, showing in dotted lines the extension bed 100 with the optical element set for long focus exposures by removal of one finder lens *l'*, and of one camera lens 82. Fig. 12 is a perspective showing how the finder image and the camera field both appear simultaneously to the operator.

45 The camera proper, Fig. 1, is a folding bellows camera of the usual construction comprising a box 23, a hinged cover 19, which opens and locks at right angles to serve as camera bed, a bar 50 adapted to slide in and out on the bed, and a lens carrying frame which is adapted to be clamped on bar 50 at any desirable point or unclamped and pushed back into box 23 for folding. The in and out motion of bar 50 being limited, the lens frame should for my purpose preferably be clamped to bar 50 at the point which will give the lens all the freedom of motion desirable and not more. I, therefore, provide bar 50 with a projecting lug 90, against which the lens

carrying frame is brought to bear before it is clamped.

Fastened to the side of the lens carrying frame by screws u , v and v , Fig. 3, is a box-like frame comprising side walls n which are connected at the rear by a vertical wall t , Fig. 3, and above by a top wall x . This top wall carries a lug y , Fig. 3, and the side walls n carry coöperating lugs z , Fig. 4, to serve as abutments for a lens l which is firmly held in contact with the various abutments y and z and the top wall x by a bent spring o . This spring o , shown enlarged in Fig. 5, has its lower end notched to form a tenon q which engages in a hole r formed in the rear wall t ; and this same spring o has its upper end recessed and partly turned up, as seen at 3 and at s in Fig. 5, to form a step-like notch adapted to engage the lower rear edge of the lens l . The spring o is easily pulled out of engagement with recess r to free the lens l , which can then be removed for cleaning. The lens is as easily remounted for use and its abutments x , y , z , z are so selected and arranged as to insure that it will always accurately and automatically return to its proper position in the finder frame or housing.

The lens l supports cemented thereon by means of Canada balsam a small total reflection prism p the hypotenuse face of which acts as a fixed mirror, and this mirror, being virtually an integral part of the lens, is surely held in and always automatically returned to its desired position. A second lens l' , which does not have to be so accurately set, is kept in place by a shouldered block w which is fastened in place by a screw passing through the back wall t . The upper end of this wall t is provided with a rectangular opening 26 , Fig. 3, the edge of which serves as bounding line for the finder image. The side walls n at their lower front ends are perforated at 3 points to admit a rod 5 , Fig. 4, which is bent back upon itself at 13 to form a shorter but parallel branch $5'$. This shorter branch serves as a lock to prevent any rotation of 5 and it also acts as a support for the spiral spring 6 . By taking hold at the bend 13 , rod 5 and its shorter branch can easily be slipped into position and they are effectively held in place against removal, by friction, as soon as pressure is applied to spring 6 . Rod 5 serves as a pivotal axis for a base plate 4 , Figs. 3 and 6, which carries the total reflection prism c .

The two rearwardly converging sides of plate 4 are folded down to form stiffening flanges 9 , one of which, 9 in Fig. 3, is extended to form the lever arm m . At their forward end 10 the two flanges become parallel and are shaped to coöperate with the downwardly bent lugs 11 , 11 in forming two angular or V bearings 12 adapted to rest

directly on axis 5 . The front of plate 4 has two upwardly turned lugs 7 , 7 , Fig. 6, and the rear edge has an upwardly extending flexible hooked arm 8 , Figs. 3 and 6. The prism c is mounted by resting its lower edge on 4 and against the lugs 7 , 7 and then snapping its upper rear edge in under the hooked end of flexible arm 8 . This simple form of mount permits of easily removing the prism for cleaning its reflecting hypotenuse face. The base plate 4 is provided with a keyhole slot 16 , Fig. 6, which terminates in a central depression 27 . This depression 27 admits and holds the head $16'$ of a pin 15 , Fig. 3, which is swiveled at 14 to the movable end of spring 6 . The lower end of this pin 15 , Fig. 3, is used as a handle for connecting and disconnecting the spring 6 with the base plate 4 while the latter is in place on axis 5 .

The fixed end of spring 6 is hooked over the lower edge of the inside wall n , and this hook suffices to hold the spring against accidental removal, provided the spring 6 has been connected to plate 4 . Spring 6 acts to pull the two bearings of plate 4 firmly down into contact with rod 5 and to keep the end of arm m pressed in contact with the cam face k of plate 17 . The latter has slots 20 , 20 and clamp screws 21 , 22 providing for vertical adjustment on a base block 18 which is rigidly fastened to the base 19 , Fig. 1, of the camera. This simple arrangement permits of adjusting the inclined plane or cam k , so it shall answer for any lens, whatever be its focal length. To make this adjustment easier and more certain (with lenses of approximately the same focal length) I have designed the device so that the lever m shall, when the camera is in focus on a very distant object, be in contact with said cam immediately over screw 21 . Two observations then will in all cases suffice to set the cam or to correct its set if it should have become deranged, and this without any necessity whatever for actually determining the focal length of the lens.

The process of adjustment is as follows: The camera is mounted on a firm base or tripod and first focused by the usual method on a very distant object. The operator, then looking in the finder, will, if the device is out of adjustment, see the distant object broken. He then loosens screw 21 , and, while looking in the finder, mends the broken image of the distant object by lowering or raising cam k at its rear end about the forward screw 22 as a pivot and, when the image is mended, he tightens screw 21 and loosens screw 22 to prepare for the second operation. He now focuses by the usual method on a near object; then, looking in the finder, he mends the broken image of the near object (if such image should appear broken) by raising or lowering the forward screw 22 .

- end of the cam about screw 21 as a pivot and then clamps screw 22. It will be noted that the first adjustment for the distant object is not appreciably disturbed by the adjustment for the close object because the latter adjustment has no tendency to either raise or lower the point of the cam which is immediately over screw 21, and which, as stated above, is the point corresponding approximately to the set for infinity. Where the lever m bears during the second adjustment is not material, although it would be better to have it at about one-sixth from the extreme outer end of its stroke. When the camera is folded up the objective carrier is pushed back into case 23 of the apparatus, and lever m falls from cam k into a position such as to occupy as little place in length as possible so it can easily lodge itself in case 23, the same as all the other parts of the finder. An opening in the rear wall t is provided, Fig. 3, to allow the prism c to turn as far back as is necessary to make lever m come well forward.
- 25 A diagonal cross 24 on the nearly vertical face of prism c , Figs. 2 and 4, serves indirectly as a bead sight for the eye which will be known to be in a correct position when the cross is seen in the finder in the center 30 of the fixed mirror p which serves as peep sight. To facilitate the correct placing of the eye, that is, to facilitate finding the image of the cross in the peep mirror p , I provide on the camera box 23 a mark 35 Figs. 1 and 2. The cross being traced on the vertical face of the prism, its image does not change place visibly in the finder in spite of the oscillations of the reflecting prism c ; because in the adopted arrangement the visible image of the cross, though movable, does not appear to move, for it moves in a direction coincident with the line of sight. Where the frame t n is to be fixed to the camera without adjustment, the 40 upper reflector p should be adjustable about an axis through lugs z z , Fig. 4, and to secure this adjustment all that is necessary is to make stop y , Fig. 3, adjustable in a line parallel with the principal axis of the camera. Such adjustment, shown at 62 in 45 Figs. 7^a and 7^b, Sheet one of the drawings, raises or lowers the apparent position of the centering cross as seen in the finder, and, therefore, serves to make the center of the 50 finder image correspond with that of the camera image. Parts L, P, Z, Z, X, X, and Y in these Figs. 7^a and 7^b correspond to those parts of the other figures that have the corresponding lower case letters.
- 55 The lenses l and l' , or L , which I have shown as preferable, are divergent lenses; but I do not limit myself to the use of a divergent lenticular system or even to a lenticular system. In the lenticular systems, 60 lenses of any plus or minus focal length

might be used, and even those in which the focal length is infinite; that is, glass with flat faces neither convergent nor divergent may present advantages. The glass may be a simple wedge, or if no drop in the line of sight is required a piece of plain glass will do, and in the latter case a frame corresponding to the outline of the plate is often all that is necessary. When the margins of a picture are secondary, the focusing finder 70 reduces itself to the reflectors set as if the field limiting means were present, and so as to act, therefore, as centerers; that is, as means for centering the image on the plate without determining its extent. 80

The fundamental principles involved in the structure of my Figs. 1 and 2 are elucidated in Fig. 8, where the reflector c is shown set parallel with relation to p , from which it is separated in this its parallel position by a distance of b centimeters. The object d to be photographed emits two distinct groups of rays: one group that proceeds directly from d through lens l to form the image f ; and a second set that proceeds by 90 reflection on c and then on p to form: first, the full size image g in mirror c ; then the full size image h in mirror p ; finally the reduced image i in lens l . As the separation of the mirrors c , p in this their parallel relation is b centimeters, the image h must be offset with relation to the object d back and upwardly through a distance equal to $2b$ centimeters, so that the lens l forms an image 95 i of h which is similarly offset back and upwardly from the image f . In speaking of the images f , g , h and i as being "formed" I use the term "formed" as it is always used in the science of optics; that is, without alleging anything as to visibility. What parts 100 of an image are visible, and what parts are not visible, depends upon proportions, relative positions, and other conditions; principally upon the relative position of the observer's eye. In Fig. 8, for instance, the eye 105 sees the parts of image f which are not hidden by reflector p ; that is to say, those that are not comprised in the angle alpha (α). Likewise it sees of the image i the part corresponding to the rays which are sent by 110 mirror p ; that is to say, the parts that are comprised in this same angle alpha (α). But because of the offset mentioned above the visible part of this image i comprised 115 in the angle alpha (α) does not correspond to the part of the image f comprised in the same angle; it follows, therefore, that when the object d is not at infinite distance and the mirrors p c remain parallel the eye sees 120 of the object an incomplete image, the missing part of which is filled by a portion of another image, which does not register or match with the first. If the missing part of the first image corresponds to the middle of the eyebrow of a person being photographed, 125 130

Fig. 9, this middle part of the eyebrow is seen in the finder as a part of the other image, and consequently is raised so that the eyebrow looks as if broken into three parts. By proper angular displacement of mirror c , however, to shift image i , the latter may be brought into apparent coincidence with the image f , so that the eye shall see in the finder only one image that is complete and without any discontinuity. The angle through which reflector c must be turned about pivot j to obtain this apparent coincidence depends on the distance of the object. When the object is far off or at infinity the linear distance $2b$ centimeters between this object d and its image h appears so small as to be negligible; that is to say, that the two images f and i practically coincide, with the mirrors parallel. As the object approaches, however, the two images f and i separate, and separate more and more so that the reflector c must be turned through an angle that is larger and larger to secure coincidence. On the other hand, the camera objective has to be moved away from the photographic plate to keep the approaching object in focus; and there is necessarily a definite relation between the extent of these displacements and the amplitudes of the corresponding rotations which must be imparted to reflector c to secure coincidence in the finder.

The exact law connecting mirror inclinations with camera extensions is shown in Fig. 23 of my said Case A, in which the mirrors M^4 and N^4 correspond, respectively, to the present mirrors c and p , and as a result thereof the same is necessarily curved, its curvature being greatest at the highest point of the cam to lessen gradually as the cam falls. Where, therefore, a straight cam is used, such as k in Fig. 1, the device is not "theoretically accurate" and it can only be exact for two different distances of the object point. Where the object point to be focused on is too small to be conveniently divided by the edge of prism p , my mirrors are set as explained in connection with Figs. 14 to 16 of my said Case B to offset the vertical path of the movable image.

The path of the movable image may be offset horizontally to any desired degree by means of the arrangements shown in Figs. 7, 7^a, and 7^b, used for tilting the mirror p about a horizontal axis parallel to the axis of the camera lens. The normally fixed mirror p , therefore, has two distinct angular adjustments that differ in kind and in purpose, to wit: first, one angular adjustment produced by lug Y , Fig. 7^b, and which takes place on the transverse horizontal axis $z z$; secondly, a second adjustment produced by screw 60, Fig. 7^a, and which takes place about a longitudinal axis parallel to the camera lens. The first on $z z$ as axis raises

or lowers the line of sight passing through the fixed mirror p by raising or lowering the image in p of the cross lines reflected in the lower mirror c ; and the second adjustment produced by screw 60, Fig. 7^a, serves to horizontally offset the vertical path of the movable image with reference to the object. 70

To sum up: when my finder is used to locate the image on the plate, and also for focusing the same, it is always arranged so as to produce two images of all objects that are examined with it and its mechanism is combined with that of the camera so that the operator can by the relative position of the two images judge whether the object is 75 or is not in focus and in which direction it is out of focus so he may easily bring it without hesitation quickly into sharp focus.

It will be seen in Fig. 8 that the observer's eye is higher than the finder and that the rays included in angle gamma (γ) proceed from the object toward the eye by passing directly over the finder. This peculiar feature is highly important, as it allows the eye to see from the same point and at will 80 without any movement of the head or of the apparatus the object itself over the finder or its image in the finder. This property is secured by making the finder not with an ordinary lens, symmetrical with respect to 85 its principal axis, but by means of a suitably chosen asymmetrical lens. All rays emanating from the object and meeting such a lens are refracted by it in the direction of the eye as if they proceeded from the image 90 f , and are all comprised in the pencil of rays beta (β), which emerges from the symmetrical lens in its superior part; this part alone of the lens is, therefore, useful and consequently the other part shown in dotted 95 lines, being of no use whatever, is suppressed. The finder, though eccentric, has to be made in the usual form of a rectangle corresponding to the dimensions of the sensitive plate; that is to say, it is still a rectangle, but one whose center is not situated on the principal optical axis of the lens in which it is taken. This very important disposition of the finder is applicable to all 100 finders; as well to those which are used simply as finders to locate the object on the camera plate as to those which focus because it is evident that the refraction is entirely independent of the presence of reflectors c and p ; that is to say, of whether it is necessary to see in the finder the image f and part of image i , or only image f . In practice, it is not indispensable that the pencil 110 of rays gamma (γ) be outside of the pencil of rays beta (β). It is sufficient that it be 115 out of the axis of the latter; that is to say, that the finder does not hide the principal or central part of the object which is to be focused upon.

Fig. 12 is a perspective on the vertical 120 125 130

plane AC', Fig. 11, of the rear end wall 99 of the camera as perspective plane, showing how the finder and the camera as well as the camera field and finder image must 5 appear to an operator who has leveled his camera and placed his eye in a correct observing position at a distance to the rear of the camera. Point C' is the point of the perspective plane that is situated directly 10 opposite and at the same level as the observing eye. According to the rules of perspective, point C' is the image of the infinitely distant central point C of the camera field; and it is also the vanishing point of the 15 three parallel central rays CE, CF, CA of Fig. 11, as well as of all other horizontal lines parallel to the camera axis. The finder image appears with its center directly over sighting point 25. In Fig. 12 the vanishing 20 point C' is closer to the finder with long focus than with short focus because the eye in short focus work is at E, Fig. 11, while it is lower at E' for long focus work; otherwise the appearances are the same in all 25 cases. The operator places his eye at the correct elevation by positioning it to see the cross 24 appear as reflected centrally in the eye mirror, as illustrated in Fig. 12.

The part 40 of the reflecting prism p , Fig. 30 10, at the right of the line 2, 1, Fig. 8, which is drawn touching the top edge of mirror c , and the lower edge of lens l is suppressed because it is useless for reflection and causes an interruption of the images. To make the 35 line of separation between the two image fragments as sharp as possible around the whole periphery of the prism p as it appears in Fig. 8, all of the prism walls, except two, to wit, the cemented face and the hypotenuse 40 face, must converge, Fig. 10, in a point situated on the opposite side of the lens very nearly in its focal plane. The degree of convergence depending on the focal length of the finder lens ought, therefore, to be 45 different when the rear lens (in case two are used as mentioned below) is removed. But to avoid any such necessity I prefer to make the convergence a little greater than is required for the one lens and a little less than 50 would be best for the combination of the two lenses.

To simplify the explanation, I have so far spoken of the finder as composed of a single lens, but it is evident that it could consist 55 of a more complicated optical system, as, for example, of two plano-concave lenses placed one back of the other; the outside lens carrying the prism p . The double lens gives, as is well known, a better image than the 60 single lens. Furthermore, it presents a special advantage in the case where the finder is applied to an apparatus such as shown in Fig. 11 in which the objective is composite and gives at will, when used complete or in part, two different focal dis-

tances. The double lens of the finder serves then with the complete objective and, when the front of the objective is taken off to add to the focal length, the second lens of the finder must be removed at the same time, 70 Fig. 11, so as to only use the front lens and so keep the field of the finder in correspondence with the new field of the apparatus. Where the finder is thus established for two focal lengths, there should necessarily be 75 two distinct and differently inclined planes to oscillate the mirror c ; one, k , Fig. 11, which is to be used when the objective and the finder are complete; the other, k' , Fig. 11, when they are incomplete. When the 80 finder is composed of a single lens L , as in Figs. 7^a and 7^b, it is better, in order to avoid curvatures of too short radii, to use a bi-concave lens. The surface by which prism P is fixed to such a bi-concave lens has then 85 to have a convex curvature corresponding to the concave surface to which it is fixed.

The main advantages of my present invention are: first, that the camera may be manipulated as easily as if no focuser were 90 present, either to open it up for use or to fold it up compactly for transportation; secondly, that during the said folding operation the focuser automatically finds its 95 way into a heretofore unused inside recess of the folded up camera; thirdly, that the focuser, when in position of use, does not project laterally with reference to the main body of the camera; fourthly, that a positive means is provided for offsetting the 100 apparent path of the movable image in and in any desired degree through and including zero value; fifthly, that the finder image appears as a reduced copy of the original object situated directionally close by such original. 105

What I claim as my invention and desire to secure by Letters Patent is:

1. As an attachment for cameras, the combination with a lens, of a reflecting prism with tapering sides, cemented thereon, and 110 a second reflector, coöperating with the lens and prism, to form duplicate images of an object viewed in the lens.

2. As an attachment for cameras, the combination with an eccentric divergent lens, of 115 a reflecting prism cemented thereon, and a second reflector, coöperating with the lens and prism, to form duplicate images of an object viewed in the lens.

3. As an attachment for cameras, the combination with a lens and a reflecting prism cemented thereon and a second reflector pivoted to coöperate with the lens and prism in forming two relatively movable images of an object, of means for adjusting the lens on an 120 axis perpendicular to the pivot of the pivoted reflector.

4. As an attachment for cameras, the combination with a lens and a reflecting prism cemented thereon and a second reflector piv- 125

- oted to coöperate with the lens and prism in forming two relatively movable images of an object, of means for adjusting the lens on an axis perpendicular to the pivot of the 5 pivoted reflector, and other means for adjusting it on an axis parallel with such pivot.
5. The combination with a folding camera and its finder, of automatic means for 10 mutilating the finder image when the camera is out of focus, such means being adapted to automatically open and fold up with the camera.
6. The combination with a camera having 15 a compound objective which may be used whole with short focus or in part with long focus, of a finder having means to change its field to correspond with that of the objective.
- 20 7. The combination with a camera having a compound objective which may be used whole with short focus or in part with long focus, of a finder having means to change its field to correspond with that of the objective and without changing the size of the 25 finder image.
8. The combination with a camera having a compound objective which may be used whole with short focus or in part with long focus, of a finder comprising two lenses, and 30 means for unmounting one of them so the finder may be used with single lens or with compound lens in the same manner as the camera.
9. The combination with a camera having 35 a compound objective which may be used whole with short focus or in part with long focus, of a finder comprising two eccentric lenses, and means for unmounting one of them so the finder may be used with single 40 lens or with compound lens in the same manner as the camera.
10. The combination with a camera and its finder, of means for forming the finder image directionally close by the original object and automatic means for mutilating the 45 finder image when the camera image is or would be out of focus.
